[57] CLAIM

The ornamental design for a chair, as shown and described.

DESCRIPTION

FIG. 1 is a perspective view taken from the front right side of a chair embodying my new design;

FIG. 2 is a front elevational view, on a reduced scale, of the chair shown in FIG. 1;

FIG. 3 is a rear elevational view, on a reduced scale, of the chair shown in FIG. 1;

FIG. 4 is a left side elevational view, on a reduced scale, of the chair shown in FIG. 1;

FIG. 5 is a top plan view, on a reduced scale, of the chair shown in FIG. 1; and

FIG. 6 is a bottom plan view, on a reduced scale and reoriented 180 degrees, of the chair shown in FIG. 1.

*FIG. 1**FIG. 2**FIG. 3**FIG. 4*FIG. 5
